CONCRETE ROOF SUPPORT

Marvin L. Rich, 1018 Opal, Boise, Idaho 83705

Filed Apr. 9, 1971, Ser. No. 132,923

Term of patent 14 years

Int. Cl. D8—08

U.S. Cl. D8—235

FIG. 1 is a right side elevational view of the concrete roof support embodying my new design.

FIG. 2 is a rear elevational view.

FIG. 3 is a left side elevational view.

FIG. 4 is a front elevational view.

I claim:

The ornamental design for a concrete roof support, substantially as shown.
